UNITED STATES PATENT OFFICE.

HARRY J. MOREY AND DON N. THOMPSON, OF SYRACUSE, NEW YORK, ASSIGNORS TO
PASS & SEYMOUR INC., OF SOLVAY, NEW YORK, A CORPORATION OF NEW YORK.

SWITCH MECHANISM.

Application filed August 22, 1921. Serial No. 494,188.

To all whom it may concern:

Be it known that we, HARRY J. MOREY and DON N. THOMPSON, citizens of the United States, and residents of Syracuse, 5 in the county of Onondaga and State of New York, have invented a certain new and useful Switch Mechanism, of which the following is a specification.

This invention has for its object a switch mechanism particularly applicable for lamp sockets and especially adapted for what are called double pull chain switches or indicating pull switch, which mechanism is extremely simple in construction, economical 15 in manufacture and highly efficient and durable in use. The invention consists in the novel features and in the combinations and constructions hereinafter set forth and claimed.

20 In describing this invention, reference is had to the accompanying drawings, in which like characters designate corresponding parts in all the views.

Figure 1 is a vertical sectional view of my switch mechanism showing the same embodied in a lamp socket which is also shown in vertical section.

Figure 2 is an end view looking upwardly in Figure 1, parts being broken away.

25 Figure 3 is a plan view looking downwardly on the upper section or block of the lamp socket, the casing being removed.

Figure 4 is a plan or upper face view of the lower section or block of the socket.

30 Figure 5 is a vertical sectional view taken on the plane of lines 5—5, Figure 4.

Figure 6 is an enlarged plan view of the switch member.

Figure 7 is an enlarged view on the plane 40 of lines 7—7, Figure 6.

Figures 8 and 9 are respectively a vertical longitudinal sectional view and an inverted plan view of our switch mechanism applied to, or embodied in, a flush wall switch, the bottom plate of the insulating body or housing for the mechanism, being removed.

Figure 10 is a plan view, the wall plate being partly broken away.

45 Figure 11 is a sectional view parts being removed.

Figure 12 is a detail view of the switch member.

50 This switch mechanism comprises generally, a reciprocally movable switch member,

an actuator therefor movable reversely relatively to the switch member, spring means movable with the actuator and arranged to thrust at the inclined angle against the switch member to shift the switch member in one direction, the actuator being movable to reverse the angle of inclination of the spring means relatively to the switch member in order to cause the spring to move the switch member in the opposite direction. 60

This switch mechanism is here shown as embodied in a lamp socket which may be of any suitable form, size and construction, it being here shown as consisting of upper and lower sections or blocks of insulation 1, 2, 70 provided with suitable recesses in their opposing faces for the switch mechanism, and the outer or sleeve terminal 3 mounted on the lower section 2 of insulation, a central terminal 4 also mounted on the lower section 2, the outer terminal 3 being connected by means of a conductor 5 to a wire terminal 6 and the central terminal being connected by the conductor 7 to a switch contact 8, which is connectible to and disconnectible 80 from the second switch contact 8^a to the movable switch member. The contact 8^a is connected to the other wire terminal 6^a.

These contacts 8, 8^a are exposed in recesses in the upper side of the lower block of insulation 2 separated by the barrier 9. The lamp socket also includes a suitable casing 12, which may be of any suitable form, size and construction.

13 is a shiftable switch member which in this form of our invention is shown as a plate slideable rectilinearly or in a plane on the bottom of a recess 14 in the upper side of the block 2 of insulation, or upon a piece of insulation 15 at the bottom of the recess 14 and as having prongs or arms 16, 17, for engaging respectively, the contacts 8, 8^a. The switch member further includes a strip of insulation 18 on the upper side thereof which is held in position by upturned ends 19 and 20, on the switch member. The switch member is formed up from sheet metal. 90

21 is the actuator which is here shown as reversely movable relatively to the sliding movement of the switch member and as 105 movable in an arc or about an axis. The actuator is here shown as a yoke, the arms of which have outturned lugs or trunnions 22 at their ends mounted in suitable bearings 23 therefor in the block 2 in the sides and 110

near the bottom of the recess 14, the yoke being arranged with its pivotal axis extending crosswise of the path of movement of the switch member.

- 5 The spring means comprises a spring 24 movable with the actuator 21 and extending or arranged to thrust in a general direction radially to the axis of the actuator 21, and also preferably a guide for the spring, as 10 a push bar or pin 25.

As here shown, the spring 24 encircles the push bar or pin 25 which is slidable at one end through an opening 26 in the intermediate part of the yoke 21 and has its 15 other end pivotally connected to the switch member 13 between the ends thereof, it being here shown as having laterally extending shoulders 27 near its lower end which thrusts against the upper face of the strip 20 of insulation 18 of the switch member 13, the end of the pin below the shoulders extending into a slot 28 in the switch member and the insulation thereof.

The pivotal connection between the push 25 bar 25 and the switch member 13, that is, the point at which the shoulders 27 engage the upper face of the switch member is normally at one side or the other of the axis of the yoke 21 so that the angle of the pin 30 through which the thrust of the spring is transferred to the switch member, is at a less angle of inclination relatively to the switch member than the yoke when the yoke is in either of its extreme positions.

35 Upon movement of the yoke from one of its extreme inclined positions to the other, after the yoke passes beyond a line normally or at a right angle to the movement of the switch member, the inclination of the bar 40 25 and spring 24 is reversed and hence the spring thrusts against the switch member in a reverse direction and shifts the push bar 25 endwise and slides the switch member 13 from its "off" to its "on" position, or from 45 its "on" to its "off" position, as the case may be.

The actuator or yoke 21 is operated by means of cords or so-called chains 29 connected in any suitable manner as at 30 to the 50 intermediate part of the yoke and extending in opposite directions outwardly through the casing 12 or guide passages 31 provided on opposite sides of the casing.

Obviously, upon pulling of one cord 29 55 from the position shown in Figure 1, the position of the yoke 21 will be reversed, causing the spring 24 to thrust the switch member through the rod 25 to the right or "on" position. Then upon pulling of the 60 other chain 29 the position of the yoke member will be again reversed into its position shown in Figure 1, and the spring will thrust the switch member to the left into the position shown in Figure 1. The chains are 65 preferably the same length and may be dif-

ferently colored or otherwise differentiated. Hence, one chain will hang lower than the other and indicate whether the switch is "on" or "off."

In Figures 8 and 9, 10 and 11, this switch mechanism is shown as applied to a wall switch. 41 designates the body or housing of the switch, it being formed of a block of suitable insulating material formed with a recess 42 opening through its bottom or 75 lower side.

43 is the switch member which slides along a smooth surface provided on a strip or insert 44 on an inner face of the top wall of the block 41. The switch member is bifurcated at its ends at 45, 46 and the bifurcations move astride projections or barriers 47 depending from the top wall of the block 41. In the illustrated embodiment of this wall switch but one pair of bifurcations, those designated 45, are used to conduct the current, these bifurcations coacting with contacts 48, 49 exposed in the recess 42 on the inner face of top wall thereof and in line with the bifurcations 45, these contacts 90 being in circuit with wire terminals 50, 51, exposed in the outside of the block 41. Obviously, the other pair of bifurcations 46 may in similar manner coact with like contacts of additional wire terminals. 95

52 is the actuator reversely movable relatively to the sliding switch member 43, it being a yoke arranged astride the switch member 43, and having its intermediate portion 53 extending above the switch member crosswise thereof and its arms extending below the switch member. The yoke is provided with trunnions 54 seated in suitable bearings or notches and the intermediate part thereof is provided with a handle 55. The trunnions 54 as here illustrated, seat in notches 56 in a supporting plate 57 on the top of the block 41. The notches are formed in the upper edges of down-turned lugs 54^a on the sides of the plate 57, the lugs 100 extending in recesses in the top wall of the block 41. The intermediate part of the yoke extends in a transverse slot 58 in said plate and the handle 55 extends through a central elongated hole 58^a in said plate. The slot 58 is alined with the notches 56. The plate is provided with lugs 59 extending beyond the ends of the block and to which the wall plate 60 is secured as by screws 61. 105

The plate 57 is secured in position in any suitable manner, here as by screws 62 extending through the block from the lower or rear side thereof and threading in the plate. The screws 62 also serve to hold the cover plate 62^a for the recess 42 in position. The handle 55 of the switch extends through a slot 63 in the wall plate 60 and the slot is closed by a slide 64 fitting and movable with the handle 55 and sliding between the wall plate 60 and the supporting plate 57. 110 115 120 125 130

It is here illustrated as guided in its movement by lugs 65 which extend into slots 66 in the supporting plate 57. The plate has the words "on" and "off" thereon on opposite sides of the handle 55 and arranged to come into alinement with the ends of the elongated slot 63, the word "off" being exposed through one end of the hole when the switch is "off" and the word "on" through the other end of the hole when the switch is "on."

The spring means of this switch mechanism is substantially the same as that shown in Figs. 1 and 5, and consists of a push 15 arm 67, thrusting at one end against the switch member 43 or a bearing 68 seated in a layer of insulation 69 on the switch member 43 and a spring 70.

The spring 70 encircles the push rod and 20 thrusts at one end against a head 71 on the rod adjacent the switch member and at its other end against an abutment 72, carried by the yoke arms and formed with a guide or hole 73 in which the push rod slides. 25 The abutment is bent from sheet metal on the form of a channel and the ends thereof receive inturned lugs 74 on the yoke arms. The abutment has a rocking movement on the lugs during the movement of 30 the yoke 52.

The operation of the switch mechanism shown in Figs. 8 and 9 is the same as that shown in Figs. 1 and 5. Upon throwing of the handle 55 in one direction or the other 35 the spring 70 is tensioned as its lower side swings from one side to the other of the center line of the switch member and throws the switch member.

What we claim is:

1. In a switch mechanism, the combination of a reciprocally movable switch member, an actuator in the form of a yoke having its arms pivoted on an axis extending transversely of the path of movement of the switch member, a push pin having one end 40 slidably engaged with the intermediate part of the yoke and its other end pivotally connected to the switch member, and a spring thrusting at one end against the intermediate part of the yoke and at its other end, 45 against the pin, substantially as and for the purpose set forth.

2. In a switch mechanism, the combination of a reciprocably movable switch member, an actuator in the form of a yoke having its arms pivoted on an axis extending transversely of the path of movement of the switch member, a push pin having one end 50 slidably engaged with the intermediate part of the yoke and its other end pivotally connected to the switch member and a spring thrusting at one end against the intermediate part of the yoke and at its other end against the pin, substantially as and for the purpose set forth.

In testimony whereof, we have hereunto 55 signed our names at Soivay, in the county of Onondaga, and State of New York, this 13th day of August, 1921.

HARRY J. MOREY.
DON N. THOMPSON.
